UNITED STATES PATENT OFFICE.

CARL RYDELL, OF MANILA, PHILIPPINE ISLANDS, ASSIGNOR OF ONE-FOURTH TO PETER JOHNSON WESTER, OF LAMOA, VIA LIMAY, BATTAAN, PHILIPPINE ISLANDS.

MACHINE FOR ASSEMBLING SHOES.

1,286,790.

Specification of Letters Patent.

Patented Dec. 3, 1918.

Application filed September 29, 1917. Serial No. 194,039.

To all whom it may concern:

Be it known that I, CARL RYDELL, a citizen of the United States, residing at Manila, Philippine Islands, have invented new and useful Improvements in Machines for Assembling Shoes; of which the following is a specification.

This invention relates to machines for assembling shoes and the object is to provide a machine especially adapted to assemble the parts of a shoe similar to the shoe described in my U. S. Patent 1,208,665 issued Dec. 12, 1916.

With this object in view, the invention consists in the novel construction herein-after described and claimed.

In the accompanying drawings, forming part of this specification;

Figure 1 is a view in side elevation showing means for supporting a last in position for assembling the parts of a shoe.

Fig. 2 is a top plan view of the structure shown in Fig. 1.

Fig. 3 is a vertical transverse section 25 through the last and showing the inner and outer sole in position.

Fig. 4 is a horizontal section through the last.

Fig. 5 is a similar section taken across the 30 top of the hammers carried by a movable plate in the last.

Fig. 6 shows a portion of the shoe in side elevation with a portion of the frame for retaining the shoe and last in position within 35 the main frame shown in Fig. 1.

Fig. 7 is a top plan view of the structure shown in Fig. 6.

Fig. 8 is a perspective view of the clamping member shown in Figs. 6 and 7.

Fig. 9 is a view in elevation and in vertical section of a punching device.

Fig. 10 is a section on the line 10—10 of Fig. 9.

Fig. 11 is a vertical section showing a portion of the structure of Fig. 9 and the manner of guiding the punching device with reference to the frame on which it is mounted for slidable movement.

Fig. 12 is a perspective view of a socket for receiving a screw and securing the outer sole.

Fig. 13 is a detail in section showing a frame illustrated in Figs. 1 and 2, in position, with a screw to be inserted through the frame.

In carrying out my invention, I employ the frame comprising a plurality of up-

wardly extending branched members 10 mounted on a standard 12 and spaced apart a suitable distance at the upper end to permit of the clamping of a shoe between the 60 arms. At the upper end of standard 12 is a transverse bar 14 on which is mounted a socket member 15 supporting rotatably thereon a spindle 16, said spindle having an enlarged portion 17 provided with apertures 18 to permit of the insertion of a bar for turning said spindle.

The last comprises a metallic shell 27 including a transversely extending plate member 30 constituting the bottom of the last, 70 which in the drawings appears at the upper side, since the last is in reversed position. The position of the last with reference to spindle 16 is controlled by means of a nut 22 co-operating with the threaded portion 75 26 of the spindle, this nut being provided with apertures for rotating the element mentioned. A washer 27 surrounds the spindle above the nut, and a sleeve 28 is loosely carried by the shaft and is rigidly supported 80 with reference to the last by spider 29.

Within the hollow last or shell I mount a plate 31 having substantially the form of the bottom of the last, and this plate carries a boss 32 having threaded connection with 85 the upper end of spindle 16, whereby the rotation of the spindle by means of a short bar or pin inserted in apertures 18 raises or lowers plate 31. This plate carries a series of hammers 40, and plate 30 carries 90 a plurality of square tubular portions 33 receiving threaded socket members 41, the latter in turn receiving screws 94, as described below. The hammers serve to force or carry the sockets through the tubular 95 portions 33 and into the inner sole in assembling the shoe.

A metallic clamp 45 having a contour fitting the toe portion of the shoe is provided, and is mounted on a threaded spindle 46 100 passing through a threaded portion 47 of one of the frame members 10, the member 46 being operated by means of a wheel 48 or in any suitable manner. A complementary clamp 49 engages the heel portion of the 105 shoe and is mounted on a spindle 50 having threaded connection with another frame member 10 oppositely located. This clamp of course may be operated by a wheel or otherwise, as desired.

A marginal metallic frame 54 which may be about one inch wide and of suitable thick-

ness, is provided with a flange 55 on its inner edge and a flange 56 on its outer edge for engaging the portion of the punching device to be described below. Frame 54 is 5 also provided with holes corresponding in position to the square tubular holes 33, these being located in line with hammers 40. This frame is formed in two parts, the heel portion of the frame including two different 10 constructions, one of which is used before the heel of the shoe is attached, constituting substantially a continuation of the forward or toe portion of the frame, while the other is formed like a strap, bent as shown in Fig. 15 8, and adapted to fit over the heel portion when secured to the shoe. One of these parts is designated 60 and the other 61, and they are similarly connected to the forward portion of the frame 54 when either one is 20 employed, that is to say, projections 62 and 62', as the case may be, fit into apertures 63 formed in the transverse member 64 of frame 54.

Arms 66 and 67 are formed on opposite 25 ends of frame 54 and have pivotal connection with frame members 10 by means of bolts 68 and 69, the latter being removably mounted so as to permit of the disconnection of the portions indicated.

30 The punching device employed in connection with the present construction is formed in the manner now to be described. This device is employed for punching the holes in the leather around the margin of the upper for the accommodation of the threaded sockets 41. A metallic plate 70 about one inch long is formed with curved sides, said sides being flanged as shown at 71 for embracing the flanges of the frame 54. The 35 device must be of such size as to permit it to slide along the toe portion of the frame mentioned. Plate 70 is provided with a central aperture through which a tubular device 72 passes, this tube being resiliently 40 mounted by means of a spiral spring 73 for the purpose of holding the tube downwardly so that it will pass into the apertures of the frame and protrude at the bottom as shown. The purpose of this device 72 is 45 to guide the punch in the apertures of the frame, thereby centering the punch with reference to the central line of the threaded sockets 41. The tubular member 72 fits the apertures of the frame accurately, and the 50 punch fits the central aperture of member 72 in a similar manner. In order to facilitate the centering of the punch in the hole it is made self-adjusting by cutting away the lower portion of member 72 at an angle 55 so that when the punching device as a whole is passing along the frame, the spring 73 holding the member 72 downwardly, the 60 tendency will be for the angular portion to climb the side of a hole or aperture as the 65 punching device is advanced.

The punch proper is designated 75 and is tapered at its lower end and threaded at its upper end as indicated at 76 to permit of the ready removal of the device when worn.

70 The punch is operated by means of a lever 77 pivoted at 78 on an arm 79 carried at one end of plate 70, said lever passing between fork members 79 formed on an arm 80 connected with the opposite end of plate 75 70. A longitudinal slot 81 provides means for mounting a spring 82 bearing on the underside of lever 77 for returning it to normal position after operation. Lever 77' is provided with a slot 88 through which 80 passes a pin 85 mounted in ears 86 supported on an annular member 87 in which the punch is mounted.

The shoe is assembled in the following 85 manner:

The threaded sockets 41 are dropped within the tubular portions 33, so that they will rest on hammers 40. The inner sole 95 is then placed on the last, this sole being 90 already provided with holes for the accommodation of the threaded sockets. The upper, not shown in the drawings, is placed in position and secured, the clamps 45 and 49 being employed for forming the leather around the toe and heel in perfect shape. 95 After securing the upper the clamps just mentioned are removed.

The frame 54 with the smooth heel portion 60 attached, is then connected with the frame members 10 by arms 66 and 67, and 100 the last is raised tightly against the frame by setting up nut 22. The holes are then formed in the margin of the upper by punch 75, and the threaded sockets 41 are forced into place by turning the spindle 16 by 105 means of a bar or rod inserted in apertures 18. After the sockets have entered the apertures provided for them, the frame 54 is released at the heel portion, and a rubber gasket 90 is placed in position, and then the 110 sole 96, the heel portion 91 being attached thereto. The frame 54 is then again locked in position but with the strap portion 61 connected, and the last is again set up by means of nut 22. Screws 94 are then inserted in the holes in frame 54, the screws 115 being of such size that the heads will be admitted through the holes in the frame 54.

The screws can be set up by means of a ratchet screw driver, or any similar tool permitting the rapid operation. No effort is required for this operation, as the sole is already pressed as much as possible against the upper. The shoe is then finished with the exception of the wearing parts described 125 in my Patent No. 1,208,665 above referred to.

120 What is claimed is:

1. In a device of the class described, a 125 shell constituting a last and having guiding 130

means formed in one portion thereof, a plate movable within the shell, a spindle having threaded connection with the plate, devices for independently moving the shell and plate vertically on the spindle, hammers carried by the plate and coöperating with the guiding means, and means for clamping an upper in position on the last.

2. In a device of the class described, a shell constituting a last and having apertured guiding means formed in the bottom thereof, a plate movable vertically within the shell, a spindle having threaded connection with the plate, devices for independently moving the shell and plate vertically on the spindle, and hammers carried thereby and spaced to correspond with the aforesaid apertured guiding means.

3. In a device of the class described, a shell constituting an inverted last and having guiding means depending therefrom, said guiding means comprising a plurality of tubular members extending continuously around the outer edge of the last, a device movable vertically within the shell, hammers carried by the device last named and proportioned to enter the tubular members, means for forcing said device upwardly, and means for adjustably mounting the last.

4. In a device of the class described, an inverted shell constituting a last and having tubular guiding means depending therefrom, a plate movable within the shell, hammers carried by the plate and each positioned for supporting a threaded socket within the tubular guiding means, a spindle for supporting said plate and forcing it upwardly, and means for moving the last vertically with reference to the spindle.

5. In a device of the class described, a shell constituting a last, a plate member forming the bottom of the last, said plate having guiding means formed thereon, a plate movable within the last, hammers carried by the plate last named, and means comprising a frame having apertures formed therein registering with the guiding means, said frame being adapted to extend along the bottom of the last and conforming thereto at its outer edges.

6. In a device of the class described, a shell constituting a last and including a bottom member, tubular guiding means carried by said member, a plate, hammers carried by the plate and spaced at distances corresponding with the spacing of the guiding members, means for forcing the plate upwardly, and a frame provided with apertures spaced to correspond with the spacing of the guiding means, and adapted to retain the edges of an upper in position on the last.

7. In a device of the class described, a shell constituting a last, a plurality of tubular guiding devices formed on the bottom of the last, a plate movable within the last, means for forcing the plate into operative position, hammers carried by the plate and spaced at substantially equal distances apart and located opposite the guiding device, a frame having an open center portion and provided with apertures corresponding with the spacing of the hammers, said frame being formed with a plurality of detachable sections meeting along a line adjacent to the inner edge of the heel of a shoe to be assembled, and means controlling the position of the last with reference to the frame.

8. In a device of the class described, a last, means for adjustably mounting said last, means for clamping the toe and heel portions of an upper, and a frame extending longitudinally of the last and formed in two parts, said parts meeting along a line adjacent to the inner edge of the heel of a shoe to be assembled.

9. In a device of the class described, a frame-work including a plurality of spaced arms, clamping means mounted within said frame-work, a last also mounted in said frame with its toe and heel portions in position opposite the clamping means, a frame extending longitudinally of the last along the bottom thereof, means for pivotally connecting one end of the frame to the frame-work first mentioned, and means for detachably securing the opposite end of said frame.

10. In a device of the class described, a last constituting a shell, a movable plate mounted within the shell, hammers carried by the plate, guiding devices formed on the bottom of the last spaced to correspond with the spacing of the hammers, a frame extending longitudinally with reference to said last and conforming thereto in outline, said frame being apertured to correspond with the guiding devices, guiding means formed on the edges of the frame and a slideable member carried by the frame and retained in position thereon by the guiding means.

11. In a device of the class described, a last, means for adjustably mounting the last, means for clamping the toe and heel portions of an upper, and a frame extending longitudinally of the last and formed in two parts, said parts meeting along a line adjacent to the inner edge of a heel of a shoe to be assembled, one of said parts comprising angular members arranged to extend across the bottom of the heel portion of the shoe.

In testimony whereof I affix my signature.

CARL RYDELL.
